UNITED STATES PATENT OFFICE

CONSTANTINE G. MILLER AND CHARLES FRANKLIN CLEVELAND, OF CHICAGO, ILLINOIS, ASSIGNORS TO THE MEAKER CO., OF CHICAGO, ILLINOIS, A CORPORATION OF ILLINOIS

CONTINUOUS AUTOMATIC CLEANING AND PLATING MACHINE

Application filed July 3, 1926. Serial No. 120,314.

This invention relates to a continuously operating automatic electroplating apparatus embodying the necessary preliminary and intermediate cleaning operations between successive plating operations.

It is an object of this invention to provide an improved electroplating apparatus wherein in the complete series of operations, aside from buffing is automatically performed including the transfer of the article from one tank to another. For example, in plating steel articles, the customary procedure is to first dip them into a cleaning solution, then into an acid solution, a rinsing tank, a striking tank, another rinsing tank, a copper plating solution and a final rinse. If no buffing operation is necessary after copper plating and before nickel plating, the entire series of operations can be automatically performed in one machine, the lengths of the plating tanks determining the plating period and the current density being separately variable for each plating tank to obtain the best results with the material to be deposited.

It is a particular object of this invention to provide an improved transfer mechanism for lifting articles out of one tank and lowering them into another tank; in the case of plating tanks the plating circuit being broken the instant the mechanism starts to lift the article and/or maintained interrupted until the article is entirely immersed in the solution in order to produce an entirely uniform thickness of plate.

Other and further important objects of this invention will be apparent from the disclosures in the specification and the accompanying drawings.

This invention (in a preferred form) is illustrated in the drawings and hereinafter more fully described.

On the drawings:

Figure 1 is a fragmentary elevation of a machine embodying the features of this invention.

Figure 2 is an enlarged longitudinal section corresponding to Figure 1.

Figure 3 is an enlarged cross section thereof taken on the line III—III of Figure 2.

Figure 4 is a fragmentary top plan view of the driving end of the machine.

Figure 5 is a fragmentary section on the line V—V of Figure 2 showing the lower or horizontal operating part of the conveyor. 55

Figure 6 is a section on the line VI—VI of Figure 2 showing the overhead return of the conveyor.

Figure 7 is a section through the conveyor on the discharge or right hand side of Figure 2, as shown by the section line VII—VII. 60

Figure 8 is a section through the vertical conveyor on the left hand or loading side of Figure 2, as shown by the section line VIII—VIII. 65

Figure 9 is an enlarged fragmentary detail of the double chain engagement of Figure 8.

Figure 10 is a detail section of one of the devices for transferring articles between tanks taken on the line X—X of Figure 3. 70

Figure 11 is a section on the line XI—XI of Figure 10.

Figure 12 is a modified form of cam for the mechanism of Figure 10.

Figure 13 is a fragmentary section on the line XIII—XIII of Figure 12. 75

Figure 14 is a fragmentary detail of the vertical guide of Figure 10 taken on the line XIV—XIV of Figure 3.

Figure 15 is a section on the line XV—XV of Figure 14. 80

As shown on the drawings:

A series of rinsing, cleaning and electroplating tanks have been referred to in the drawings by the generic reference numeral 85 20, suitable end and intermediate partitions 21 being also indicated in Figures 3 and 5. As the particular order of arrangement and number of tanks will vary with different plating methods, it has been considered unnecessary to specifically show a complete series. As an illustration, one particular apparatus embodying this invention and including both copper and nickel plating operations is over one hundred feet long and has ten 90 compartments. 95

These tanks are supported on suitable framework 22, the uprights 23 of which extend above the tank to form supports for a pair of endless chains 24 which pass to the 100

right in Figures 1 and 2, just above the top of the tanks and return overhead. The particular form of the framework is immaterial from the standpoint of patentability and so need not be described in detail. The chains 24 comprise a number of plain links with hook links 26 spaced at even intervals, the chain passing over four toothed sprockets 27 at each corner of the framework, these sprockets being undercut at 28 between the teeth to provide room for the chain hook links 26 and a series of bars 29 carried along by the hooks on the chain.

These bars are retained in place during the upward movement of the chains at the right hand end of the machine by means of the guide bars 30 on the framework, which press on collars 31 on the bars to hold them against the chains. On the left or downwardly moving side of the conveyor, a second pair of chains 32 having hooks 33 operates in parallel with the main chains 24 to hold the bars up against the hooks 26 during the downward movement where the bars would otherwise drop free from the hooks.

On the chain tracks 34 on either side of the plating tanks, bus bars 35 are provided to contact square shoes 36 on the bars to feed the heavy current required to the bars from which the articles are hung to form the cathodes of the plating circuit. As different plating materials require different current densities or amperage rates for most efficient plating, the chains and framework are preferably so insulated that each plating tank bus bar can be fed from independent circuits to permit independent regulation.

On either side of the row of tanks at each partition 21 is located a transfer mechanism shown in Figure 10 and adapted to lift the bars 29 up from the chain so that the articles hanging therefrom will be lifted clear of one tank, carried over the partition and lowered into the next tank. This mechanism comprises a vertical outer guide 37 for the shoe 38 carrying a pin 39 reciprocated up and down the guide by means of a connecting rod 40 and crank 41 carried by the shaft 42 which is driven in predetermined relation to the speed of the chain sprockets (27) in order that the transfer mechanism may complete one cycle while the chain is advancing a predetermined distance between hook links 26. The pin 39 carries a lever 43, the lower end 44 of which is provided with a roller 45 engaged in the groove 46 in a cam plate 47. The upper or free end 48 of the lever 43 is forked to pick up a bar from the chain, and the groove is so formed as to cause this forked end to traverse a path indicated by successive dotted line positions indicated in Figure 10 by the letters A, B, C, D and E, the roller 45 traveling counter-clockwise in the cam groove 46. This result is obtained by offsetting the upper (49) and lower (50) peaks of the groove to tip the

free end 48 of the lever over to the side opposite the peak offset from the center line, the overhanging weight of the free end and the bar carried thereby assisting in carrying the rollers 45 past the upper peak or dead center position 49.

The modification shown in Figures 12 and 13 comprises a two piece plate cam 51 and 52 positioned by brackets 53. The guided end of the lever 43 is then formed with a pilot 54 projecting through the slot between the two cam pieces and is held in place by a washer 55 and a cap screw 56.

In the operation of this machine, the articles to be plated are hung from the bars at the left side of Figures 1 and 2, which forms the loading position, and after passing through the series of tanks at a uniform speed, are removed from the bars at the right hand or unloading position.

We are aware that many changes may be made, and numerous details of construction may be varied through a wide range without departing from the principles of this invention, and we therefore do not purpose limiting the patent granted hereon, otherwise than necessitated by the prior art.

We claim as our invention:

1. A conveyor system comprising a pair of spaced parallel endless chains, a portion of the pathway described by said chains being vertical, hanger bars propelled by said chains at fixed intervals therein, sprockets for said chains having cut-out portions to receive the ends of said bars, and a second pair of vertical chains adapted to hold said bars against the first pair of chains during the vertical downward movement thereof.

2. A conveyor system comprising a pair of spaced parallel endless chains, hanger bars propelled by said chains at fixed intervals therein, sprockets for said chains having cut-out portions to receive the ends of said bars, pairs of forked end levers mounted at intervals along the pathway of the conveyor chains, and coating means adapted to cause said levers to lift and transfer said hanger bars over obstructions adjacent said chains.

3. A conveyor system comprising a pair of conveyors positioned in parallel arrangement with an overhead return, portions of the overhead return being vertical, dogs carried at spaced intervals on said conveyors, hanger bars advanced by said dogs, and means movable with said dogs for maintaining said hanger bars in contact with the dogs on the vertical return portions of the conveyors.

4. A conveyor system comprising a pair of conveyors positioned in parallel arrangement with an overhead return, dogs carried at spaced intervals on said conveyors, hanger bars advanced by said dogs, and a second pair of vertical conveyors positioned adjacent the downward return portion of the first

mentioned conveyors and adapted to hold said bars against the first pair of conveyors.

5. A conveyor system comprising a pair of conveyors positioned in parallel arrangement with an overhead return, dogs carried at spaced intervals on said conveyors, hanger bars advanced by said dogs, pairs of forked end levers mounted at intervals along the conveyors and coacting crossheads and cams 10 adapted to cause said levers to lift and transfer said hanger bars over obstructions adjacent said conveyors.

6. A conveyor system comprising a pair of conveyors positioned in parallel arrangement with an overhead return, dogs carried at spaced intervals on said conveyors, hanger bars advanced by said dogs, means maintaining said hanger bars in contact with the dogs on the return portions of the conveyors, and 15 means adapted to lift and shift said hanger bars relative to the conveyors.

7. A conveyor system comprising a pair of conveyors positioned in parallel arrangement with an overhead return, dogs carried at spaced intervals on said conveyors, hanger bars advanced by said dogs, means maintaining said hanger bars in contact with the dogs on the return portions of the conveyors, pairs 25 of forked end levers mounted at intervals along the conveyors and coacting crossheads and cams adapted to cause said levers to lift and transfer said hanger bars over obstructions adjacent said conveyors.

8. A conveyor system comprising a pair of conveyors positioned in parallel arrangement with an overhead return, dogs carried at spaced intervals on said conveyors, hanger bars advanced by said dogs, a second pair of vertical conveyors positioned adjacent the 30 downward return portion of the first mentioned conveyors and adapted to hold said bars against the first pair of conveyors, pairs of forked end levers mounted at intervals along the conveyors and coacting crossheads and cams adapted to cause said levers to lift and transfer said hanger bars over obstructions adjacent said conveyors.

9. A transfer mechanism comprising a fixed cam plate having a groove, a transfer arm provided at its lower end with a roller positioned in said groove, a connecting rod pivoted to said transfer arm, and means for reciprocating the pivot of said arm and rod to move said arm.

55 10. A transfer mechanism comprising a fixed cam plate having a cam groove, a transfer arm having a roller at its lower end positioned in said groove, a vertical guide facing said cam plate, a connecting rod pivoted 60 to said transfer arm by means of a pivot pin, said pivot pin carrying a shoe positioned in said vertical guide, and means to reciprocate said shoe.

11. A transfer mechanism, comprising a fixed cam plate having a groove provided

with diametrically opposed peak portions, a transfer arm having a roller at its lower end positioned in said groove, a connecting rod pivoted to said transfer arm, and means for reciprocating the pivot of said arm and rod to cause the roller on the arm to move around the cam groove.

In testimony whereof we have hereunto subscribed our names.

CONSTANTINE G. MILLER.

CHARLES FRANKLIN CLEVELAND.
